CLAIM

The ornamental design for a hat brim with flush slot embedded allowing for magnet and ball marker, as shown and described.

DESCRIPTION

FIG. 1 is a top rear perspective view of a hat brim with flush slot embedded allowing for magnet and ball marker showing my new design;

FIG. 2 is a bottom front perspective view thereof;

FIG. 3 is a front view thereof;

FIG. 4 is a right side view thereof;

FIG. 5 is a rear view thereof;

FIG. 6 is a left side view thereof;

FIG. 7 is a top plan view thereof;

FIG. 8 is a bottom plan view thereof;

FIG. 9 is a perspective view of the present invention on an environmental cap as shown by the broken lines; and,

FIG. 10 is a perspective view of the present invention on an environmental visor hat as shown by the broken lines.

The broken line showing a cap and a visor as shown in FIG. 9 and FIG. 10, respectively, is included for the purpose of illustrating environmental structure and forms no part of the claimed design.
